(No Model.)

W. WRIGHT.
RUBBING IRON FOR RAILWAY VEHICLES.

No. 414,745.

Patented Nov. 12, 1889.

UNITED STATES PATENT OFFICE.

WILLIAM WRIGHT, OF WILMINGTON, DELAWARE.

RUBBING-IRON FOR RAILWAY-VEHICLES.

SPECIFICATION forming part of Letters Patent No. 414,745, dated November 12, 1889.

Application filed June 12, 1889. Serial No. 313,992. (No model.)

To all whom it may concern:

Be it known that I, WILLIAM WRIGHT, of Wilmington, county of New Castle, State of Delaware, have invented a new and useful Improvement in Rubbing-Irons, of which the following is a true and exact description, reference being had to the accompanying drawings, which form a part of this specification.

10 My invention relates to the construction of the rubbing-irons used with locomotives and railway-cars to prevent shocks between the locomotive and its tender or between two cars, and my object is to enable a close union 15 to be made and maintained between the locomotive and tender, &c., whether on a straight line or a curve, without interfering with their necessary freedom of motion.

My invention will be best understood after 20 a description of the drawings, in which it is illustrated, and its novel features are herein-after clearly pointed out in the claims, reference being now had to the drawings which illustrate my invention, and in which—

25 Figure 1 shows my improvement applied to a locomotive and to its tender, said locomotive and tender being coupled together and shown as they would stand with respect to each other on a very sharp curve. Fig. 2 is 30 a plan view showing my device in its preferred form. Fig. 3 is a view on the section-line $\alpha\alpha$ of Fig. 2. Fig. 4 is a view similar to Fig. 2, the supporting-casting and rubbing-iron being sectioned on the line yy of Fig. 3, 35 a special device for actuating the wedge being also shown. Fig. 5 is a view showing a modification of my device, being an enlargement of rubbing-iron attached to the tender in Fig. 1, with the rubbing-iron and its supporting-casting shown in section; Fig. 6, a plan for 40 securing the bolt J in the wedge I, as shown.

A is a locomotive; B, a tender; C, a coupling-link pivoted to each by pins cc .

D and E are rubbing-irons, one D made 45 with a long convex face and the other E preferably made, as shown, with a short face to abut against the convex iron D. This difference in form of the rubbing-irons is easily provided for as to locomotives and tenders; 50 but on cars it will be preferable, for obvious reasons of convenience, to have two convex irons abutting against each other.

F and F' represent castings to which the rubbing-irons are secured and which may be of any convenient kind, though I prefer to 55 form this casting as is shown by the one marked F, to adapt it for use with my preferred construction.

I will hereinafter refer to the devices on which the rubbing-irons are supported as 60 "buffer-supports."

I secure the rubbing-irons to the buffer-support in any convenient way which will not interfere with a certain degree of longitudinal motion in the rubbing-iron with respect to the buffer-support, and I provide mechanism for extending the iron to any desired distance from the support. Thus the rubbing-iron may be secured to the buffer-support by right-threaded bolts, as is shown 70 at I' I', Fig. 5; but preferably I employ a wedge between the iron and support as affording the firmest bearing and being at the same time readily adjusted. In practice I have formed the buffer-support F with an inclined face f and projecting flanges f' f', recessing the flanges along the inclined face to form grooves f² f².

f³ and f⁴ are pin-holes formed in the flanges f' f'. I form the rubbing-iron D so that it 80 will fit between the flanges f' f' and give its back an inclination corresponding to that of the face of the buffer-support, forming in it a groove or recess d', with lateral grooves d² d². Along its innermost edges d is a slotted 85 pin-hole formed in the center of the iron D, and d³ is a similar slotted pin-hole formed through the flanges which extend along the slot or groove d'.

I is the wedge, which I form with projecting ribs i i to fit into the grooves f² f² and ribs i' i' to fit into the grooves d² d², the wedge itself fitting into the groove d' of the rubbing-iron and against the face f of the buffer-support. 90

i³ i⁴, &c., are pin-holes formed in the wedges I.

G and H are pins by which the device is secured together.

As is shown in the drawings, the rubbing-iron D is inserted between the flanges f' and secured by the pin G, passing through holes f³ and slot d, the said slot permitting the iron to move to and from the support. I then in-

sert the wedge I in the buffer-support and rubbing-iron, its projecting ribs i and i' engaging with the grooves f^2 and d^2 and binding the buffer-support and rubbing-iron together. 5 (The grooves f^2 and d^2 and the ribs i and i' may be single instead of double, as shown; but the double construction is stronger and better.) It is of course obvious that as the wedge I is pushed in the rubbing-iron is 10 thrust outward, and by inserting the pin H through one of the holes i^2 i^3 i^4 , &c., and through the slot d^3 the rubbing-iron is locked in any desired position.

To make nice adjustments of the rubbing-15 iron, an adjusting-screw may be used, as shown in Fig. 4, where a bolt J is secured in a slot i^9 of the wedge and its threaded end passed through a standard K, nuts j j being secured on the bolt to secure it in place, while 20 permitting any desired change in its position and that of the wedge to which it is attached.

I do not desire to be understood as limiting myself to the exact arrangement shown, except where it is specifically referred to in 25 the claims, the construction I have described as being preferred by me being the best form in which I have embodied my invention, but obviously capable of many modifications without departure from the invention proper 30 involved in it.

I am aware that buffers have been constructed so as to have a longitudinal movement in their supports and provided with springs acting to keep them normally thrust 35 out to the fullest extent, while permitting them to yield under pressure. By my device, however, a close unyielding connection between the engine and tender is made practical as distinguished from the yielding connection of such former buffers. 40

Having now described my invention, what I claim as new, and desire to secure by Letters Patent, is—

1. In combination with a buffer-support, an extensible rubbing-iron separate from 45 said support and an intervening adjustable wedge or its equivalent, as described, whereby the rubbing-iron can be extended without impairing the rigidity of its connection to the buffer-support. 50

2. In combination with a buffer-support F, having projecting sides f' f' and a groove or grooves f^2 , a rubbing-iron D, having a curved face, a slot d' on its back, and a lateral slot or slots d^2 along the base of slot d' , and a T-shaped 55 wedge I, having one or more projecting ribs i and i' , arranged to engage the slots f^2 and d^2 , all substantially as specified, and for the purpose of making the rubbing-iron longitudinally extensible. 60

3. In combination with a buffer-support F, having projecting sides f' f' , perforations f^3 and f^4 , and a groove or grooves f^2 , a rubbing-iron D, having a curved face, a slot d' on its back, a lateral slot or slots d^2 along the base 65 of slot d' , and slotted perforations d and d^3 , and a T-shaped wedge I, having one or more projecting ribs i and i' , arranged to engage the slots f^2 and d^2 , and perforations i^2 i^3 i^4 , &c., arranged to register with the perforations f^4 and d^3 , and pins G and H, to connect the parts, all substantially as specified, and for the purpose of making the rubbing-iron longitudinally extensible. 70

WILLIAM WRIGHT.
